INDICATOR FOR LAMP HOLDERS

William R. Young, Fairfield, and Frank D. Bryant,
Stratford, Conn., assignors to General Electric
Company, a corporation of New York

Application October 31, 1939, Serial No. 302,177

4 Claims. (CL 200—167)

This invention relates to indicators, and more particularly to indicators for use with lamp holders having pull switches.

It is an object of the invention to provide an indicator so associated with a lamp holder having a pull type switch that it is possible to determine whether or not the switch is in the "on" or "off" position irrespective of whether or not the lamp is lighted. This is of importance in those cases where the power supply has failed or where the lamp has burned out.

In the accompanying drawing, Fig. 1 is a view of the indicator attached to a lamp holder and pull switch; Fig. 2 is a sectional view through the indicator; Fig. 3 is a perspective view of a portion of the indicator operating mechanism, and Fig. 4 is a sectional view along the line 4—4 of Fig. 2.

Referring to the drawing, Fig. 1 shows a lamp holder 10 provided with a pull switch operated by means of a cord or chain 11 to which an indicator 12 is attached at a point intermediate the length of the pull cord. The indicator is provided with a window 13 forming a frame for indicia 14 reading "on" or "off." The mechanism of the indicator is so arranged that a pull of the switch-operating cord will move the "on" and "off" indicia alternately in front of the window 13, in accordance with the operation of the switch mechanism of the lamp holder. A pull on the cord moves the indicator at the same time that the switch is operated.

The indicator comprises an outer cylindrical casing 15, together with a cylindrical core 16 disposed within the outer casing and spaced from the walls thereof to provide an inner chamber 17. One end of the inner core is formed with a flange 18 which mates with a corresponding flange 19 formed on a collar 20, these two elements being held in assembled relationship by the end of the casing 15 which is bent over and secured to the flanges by any suitable fastening means, such as a solder or the like. The other end of the outer casing is secured to the inner core at the point 21 by any suitable fastening means, such as solder, or the like. This means that the inner core and outer casing are held rigidly together. Slidably mounted within the inner core is a pull rod 22 keyed against rotation by means of an upper tang 23 and a lower tang 23'; the tangs slide in slots 24 and 24', respectively, in the wall of the inner core. A bearing member 25 within the core 16 guides the rod within the latter element for movement in a straight line. A cylindrical sleeve 26 is disposed within the chamber 17 and is rotat-

ably supported upon the core 16 by means of an annular ring 27 on the core, and a cooperative annular groove 28 on the sleeve. The ring 27 prevents the sleeve from being moved longitudinally on the core while, at the same time, permitting free rotation of the sleeve.

As shown most clearly by Fig. 3, the outer periphery of the sleeve 26 is provided with the indicia 14 designating alternately "on" and "off" so that as the sleeve is rotated any one of the indicia may be presented to the window 13 cut in the outer casing 15. Reciprocatory movement of the pull rod 22 is translated into rotation of the sleeve 26 by means of the cam elements 29 and 29' extending in reverse directions; respectively, from the upper and lower edges of the sleeve. The cam surfaces 29 and 29' cooperate with the tangs 23 and 23', respectively, and are so arranged that a downward pull on the pull rod rotates the sleeve through an angle of approximately 45 degrees, while retraction of the rod likewise rotates the sleeve through an angle of approximately 45 degrees. This means that a single pull on the cord 11 will turn the indicating sleeve 26 through an angle of approximately 90 degrees. Retraction of the pull rod is effected by means of a spring 30 disposed between the lower pin 23' and the bottom of the core 16.

When the rod 22 is pulled downwardly the upper tang 23 engages the upper cam surface 29 and moves the sleeve counterclockwise, as viewed in Fig. 3, through an angle of approximately 45 degrees. Inasmuch as the tang members are spaced apart a distance greater than that between the outer edges of the upper and lower cam members, the lower tang member is moved out of the way of the lower cam surface prior to engagement of the upper cam surface and key permitting rotation of the sleeve. Completion of this rotation presents the lower cam surface 29' for engagement with the lower key 23' and as the rod is returned to normal position under the influence of the spring 30 the lower key engages the lower cam surface and moves the sleeve through a further angle of 45 degrees. In this way the sleeve 26 is moved through a total angle of 90 degrees by a single pull on the rod through the action of the upper and lower cam surfaces. Since the indicia 14 are disposed at angles of approximately 90 degrees around the periphery of the sleeve, a single pull on the rod will move the indicia framed in the window from "off" to "on," or vice versa, as the case may be. The lower end of the rod 22 is provided with a clip 31 for receiving one end of a portion of the pull cord or chain 11, while

the upper end of the collar 28 is similarly connected to another end of the pull cord thereby positioning the indicator at a point intermediate on the length of the cord.

- 5 In operation the indicator is manually set in accordance with the setting of the pull switch incorporated in the lamp holder 10, so that as the light is turned "on" or "off" by pulls on the cord 11, the indicator will likewise be moved to present 10 the corresponding indicia 14 before the window 13 thereby indicating the position of the switch in the lamp holder. Such an arrangement is particularly desirable in those cases where the supply of current to the lamp holder may be cut off 15 to avoid leaving the lamp turned on. Conversely, when the current is turned on the indicator will let it be known whether or not the lamp is burned out or dislocated in the socket, since it will be known whether or not the switch is in "on" position. The indicator is made of a compact form 20 and of pleasing appearance. It may readily be incorporated in existing installations simply by breaking the pull cord 11 and inserting the indicator in the length thereof.
- 25 What we claim as new and desire to secure by Letters Patent of the United States, is:
1. In combination, a lamp holder provided with a switch operated by a pull cord and an indicator having relatively movable members connected in- 30 to the pull cord, said members being movable by pulls on the cord, said indicator being provided with means operated by said relatively movable members to indicate the "on" and "off" position of the switch.

2. In a device of the class described, two coaxial cylindrical members having a space therebetween, an element rotatably mounted in the space between said members, and having indicia thereon, a window in said outer member cooperating with 5 said indicia, a pull rod slidably mounted within the inner member and being provided with spaced projecting keys, and a cam on said rotatable element having reversed cam surfaces cooperating with said keys whereby slidable reciprocation of 10 said rod rotates said indicating member.

3. In a device of the class described, a casing having a window in the wall thereof, a hollow cylindrical member within said casing, a rotatable sleeve surrounding said member and having indicia adapted to be framed in said window, said sleeve being provided with cam surfaces extending in opposite directions, a pull rod mounted for reciprocating movement within said cylindrical member and having spaced keys extending 20 through slots in the member for engaging said cam surfaces, and spring means biasing one of said keys into engagement with a corresponding cam surface.

4. In combination, an electric device controlled 25 by a switch operated by a pull cord and an indicator having relatively movable members connected into the pull cord, said members being movable by pulls on the cord, said indicator being provided with means operated by said relatively movable members to indicate the relative positions of the switch.
